UNITED STATES PATENT OFFICE

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

COIL TERMINAL

1,400,038.

Specification of Letters Patent. Patented Dec. 13, 1921.

Application filed April 26, 1918. Serial No. 231,013.

To all whom it may concern:

Be it known that I, HENRY C. EGERTON, a citizen of the United States, residing at Passaic, in the county of Passaic, State of New Jersey, have invented certain new and useful Improvements in Coil Terminals, of which the following is a full, clear, concise, and exact description.

This invention relates to coils or windings 10 of the type which is employed for electrical purposes.

The principal object of this invention is to provide an improved attaching means or terminal for such coils.

In many cases it is necessary to form coils 15 of a very fine wire. When such coils have been completed and it is desired to combine them with other electrical apparatus, considerable difficulty may be encountered in connecting the ends of the coil winding with other conductors or binding posts. In making such connections, the ends of the winding oftentimes break thus necessitating the 20 unwinding of a portion of the coil in order to have a sufficient length of conductor for the making of such connections. This can, however, be accomplished if the outer end breaks, but if the inner end breaks, this 25 course cannot be followed since the inner turns of the coil are not readily accessible. The terminal of the present invention is designed to overcome this difficulty. Difficulty is often experienced in positioning small 30 coils in proper operative position on electrical devices, particularly where it is not possible or desirable to support the coil on a core. The terminal of this invention is not only adapted to serve as a terminal, but may also 35 serve as a means for supporting the coil.

In accordance with a feature of the invention, a coil is provided with an attaching means which is adapted to be secured by the convolutions of the winding and is so arranged that it does not appreciably alter the 40 shape or size of the coil.

In accordance with a related feature of the invention, a coil is provided with a pair of insulated conductors having a loop portion, which portion is embedded in the body 45 of the coil during the process of winding. The two conductors, therefore, each present two ends which project from the end surface of the coil, of which one end is adapted to be associated with the inner or outer end of the

winding, while the other end serves as an attaching means or terminal for the coil.

In the accompanying drawing, Figure 1 shows a plan view of a coil illustrating one embodiment of the invention; Fig. 2 is an elevation partly in section of the coil shown in Fig. 1; Fig. 3 is a plan view showing a modified form of the invention; Fig. 4 is an elevation partly in section of the coil shown in Fig. 3; and Fig. 5 is a perspective of the coil shown in Fig. 1, showing a method for supporting the same.

Referring now to Figs. 1 and 2 and the particular embodiments of the invention illustrated therein, 4 represents the coil support which may be of any suitable material. 70 The coil thereon comprises a body portion 5 which is formed of a plurality of layers of fine wire. The attaching means or terminals, 6 and 7, are formed of a stranded flexible wire of a diameter which is relatively 75 larger than that of the winding forming the body portion of the coil. By forming these conductors of flexible wire, the ends forming the terminals may be moved about more freely without in any way affecting the other 80 ends of the conductors to which the ends of the winding are secured. This feature is especially true where the flexible conductor is composed of a plurality of strands. These conductors have a loop portion 8 which is 85 embedded in the coil during the process of winding. The inner end of the winding is secured to one end of the conductor 6, while the outer end is secured to one end of the conductor 7. The other ends of these conductors 6 and 7 thereby serve as an attaching means or terminals for the coil. Since the conductors 6 and 7 are embedded in the body portion of the coil, any strain that might come upon the terminals will not result in injury to the ends of the coil which would necessitate the unwinding of a portion 90 of the coil.

In forming the coil after a predetermined number of layers of wire have been wound 100 upon the coil support 4 which is preferably of a strong paper tube, the winding machine is stopped and the loop portion of the insulated conductors 6 and 7 is then positioned on that portion of the coil which has already 105 been wound, in such a manner that when the winding is complete the loop portion will be securely anchored by the remaining turns

of the winding. When the winding is completed, a few turns of serving is wound thereon, after which the coil is impregnated in any suitable material in order to insure good insulation and greater rigidity. After the process has been completed, the inner and outer ends of the winding are connected to their respective terminals or attaching means as hereinbefore described.

10 In the preferred form of the invention as disclosed in Fig. 1, it is evident that the conductors forming the terminals of such a coil are adapted to be used as an attaching or supporting means for such a coil. In Fig. 5, the coil of Fig. 1 is shown suspended from a rod or supporting means 9, by the conductors 6 and 7. It will be seen from this figure that where it is impossible to support the coil by means of a core or even 20 by the sides of the coil itself, this method can be used to a good advantage.

Figs. 3 and 4 illustrate a modified form of the invention in which the terminals or binding posts 10 and 11 are formed of a 25 punching of metal or other suitable material, one end of which is secured by the convolutions of the winding, the other ends thereof projecting outwardly from the end surface of the coil. The portion of the 30 terminals or binding posts 10 and 11 which are secured by the convolutions of the winding are covered by an insulating member 12 to prevent the terminals from coming in 35 electrical contact with the turns of the winding. The ends of the winding may be wrapped around the respective terminals. Connection may then be made directly to the ends of the winding after they have been wrapped around the binding posts or terminals, or directly to the metal punching.

What is claimed is:

1. An electrical coil comprising a winding, and a conductor having a loop portion inserted between the convolutions of the winding with the ends thereof projecting beyond the surface of the coil structure to provide a terminal for the ends of the winding and a support for the coil structure.

2. An electrical coil comprising a winding and an insulated conductor having a loop portion interposed between adjacent convolutions of said winding with the ends thereof projecting beyond the surface of the coil structure, one end of said conductor being connected to an end of said winding, the other end of said conductor serving as a terminal for said coil.

3. An electrical coil comprising a winding and a conductor of a diameter relatively larger than that of said winding having a loop portion embedded in the body of the coil with the ends thereof projecting beyond the surface of the coil structure, one end of said conductor being connected to an end of said winding, the other end of said conductor serving as a terminal for said coil.

4. An electrical coil comprising a winding and a flexible conductor having a loop portion anchored within and by a portion of the winding with the ends thereof projecting from the surface of the coil structure, one end of said conductor being connected to an end of said winding and the other end of said conductor serving as a terminal for said coil.

In witness whereof, I hereunto subscribe my name this 23rd day of April A. D., 1918.

HENRY C. EGERTON.
